HEATING SYSTEM AND CONTROL
MEANS THEREFOR

Walter S. Landon, Detroit, Mich., assignor to Detroit Lubricator Company, Detroit, Mich., a corporation of Michigan

Application September 15, 1941, Serial No. 410,842,
which is a division of application Serial No.
218,720, July 11, 1938. Divided and this application
October 28, 1943, Serial No. 508,001

3 Claims. (Cl. 236—1)

My invention relates generally to heating apparatus including a liquid fuel burner, and more particularly to means for controlling the operation of the burner.

One of the objects of my invention is to provide an improved, electrically operated valve for controlling the flow of liquid fuel to a liquid fuel burner.

Another object is to provide a self-contained control apparatus for supplying liquid fuel to an oil burner to maintain a substantially constant temperature in a hot water tank.

The invention consists in the improved construction and combination of parts, to be more fully described hereinafter and the novelty of which will be particularly pointed out and distinctly claimed.

In the accompanying drawings, to be taken as a part of this specification, I have fully and clearly illustrated my invention, in which drawings—

Figure 1 is a view showing diagrammatically my control apparatus installed in a hot water heating system;

Fig. 2 is a view showing a schematic diagram of the electrical circuit embodied in my invention, and its interrelation with an oil burner for heating water;

Fig. 3 is a top plan view of my apparatus with the top cover removed;

Fig. 4 is a view along the line 4—4 of Fig. 3, looking in the direction of the arrows but with the top cover in place;

Fig. 5 is a view along the line 5—5 of Fig. 3, looking in the direction of the arrows but with the top cover in place;

Fig. 6 is a view along the line 6—6 of Fig. 5, showing only the electrical control apparatus and its supporting block;

Fig. 7 is a view along the line 7—7 of Fig. 3, looking in the direction of the arrows;

Fig. 8 is an enlarged plan view of the switch means as seen in Fig. 4;

Fig. 9 is an enlarged detail view in section of a thrust spring and its cooperating parts, and

Fig. 10 is a side view of the bowed thrust spring in an inert position apart from the rest of the apparatus.

Referring to the drawings by characters of reference the numeral 1 represents a chambered casing having an open top wall 2 over which a cover member 3 is secured, as by means of screws 4. The cover member 3 has a tubular, upwardly extending portion 5 which forms a chamber 6 having side walls 7, 8 and end walls 9, 10. The

bottom wall of the chamber 6 is formed by a plate 12 held, as with screws 13, to the member 3. The upper wall of the chamber 6 is formed by part of a cover member 15 secured by screws 15^a threaded into a pair of bosses 15^b projecting inwardly into chamber 6 from the walls 7, 8. The cover member 15 has a downwardly extending portion 16 which forms the side walls of a second chamber 17 located on top of the cover member 3 of the casing 1. The chamber 17 has a portion of the cover member 3 for its bottom wall and a portion of the cover member 15 for its top wall. The end wall 9 of the chamber 6 forms an end wall of the adjacent chamber 17 and separates chamber 17 from the chamber 6. The opposite end wall of the chamber 17 is formed by an upwardly extending portion 17^a of an L-shaped angle piece 17^b secured by one of each of the screws 4 and 13 to the cover member 3. The portion 17^a has a pair of apertures, therethrough each of which receives a "BX" terminal fitting 17^c. The portion 17^a at the top thereof carries a threaded lip 17^d which receives a screw 17^e for securing the cover member 15 thereto. Secured to the bottom wall of casing 1 is a strainer chamber 18 having an inlet means 19 connected by means of a conduit member 20 to a suitable source of liquid fuel supply (not shown). The chamber 18 has an outlet 21 leading to a constant level chamber 22 within the casing 1, and the flow of fluid through the outlet 21 into chamber 22 is controlled by means of a float valve 23 which maintains a predetermined constant liquid level within chamber 22, along the line L—L.

A U-shaped electric magnetic means 24 is located within chamber 6 and comprises a laminated core 25 having one leg 26 secured by means of screws 27 to the plate 12. The other leg 28 of the core 25 is spaced above leg 26 and carries an electrical coil 29 which surrounds and is concentric therewith. Lead wires 30, 31 connect the coil 29 to binding posts 32, 33 located in a molded block 34 made of suitable material, such as Bakelite, and which block 34 is to be hereinafter described. The coil 29 is operable to induce a magnetic flux in the core 25 so that a laminated armature 35 having one end hinged at the open end of the leg 26 is operable upon energization of the coil 29 to pivot so that the other end of the armature 35 will be urged into engagement with the open end of the leg 28 to close the magnetic circuit between the open ends of the legs 26, 28. The armature 35 has a portion 36 which extends upwardly toward the top wall portion of the cover member 15.

A bell crank lever 37 is pivoted at the intersection 38 of its horizontal arm 39 and its vertical arm 40 by a pin 41 which is received within an aperture through and secured to the lever 37, as by peening 42. The pin 41 is journaled in a boss 43 projecting inwardly into the chamber 6 from the side wall 7, intermediate the end wall 9 and armature 35. The leg or arm 39 of the bell crank lever 37 has its end portion rounded, as at 44, and received between shoulders 45, 46 of a valve member 47. The valve member 47 is located intermediate the boss 43 and end wall 9 and extends vertically downward through an aperture in the plate 12 into the chamber 22. The lower end of the valve member 47 cooperates with an outlet means 48 of the chamber 22 to control flow of fluid from the chamber 22 by reason of its vertical spacing relative to the outlet means 48. The outlet means 48 is connected by a conduit means 49 to a liquid fuel burner 50, as shown in Fig. 1. The upper end of the valve member 47 is guided for reciprocal movement within an aperture 51 in an internal boss 52 projecting inwardly into chamber 6 from the side wall 7. A pair of stop members 53, 54 are adjustably held in the boss 52 and cooperate with the valve member 47 to limit upward and downward movement respectively thereof relative to the outlet means 48 and thereby limit the maximum and minimum flow respectively of fluid from the chamber 22.

Projecting from the wall 8 and extending inwardly therefrom into chamber 6 is a boss 55 having rigidly secured thereto, as by screws 55^a, an upwardly extending carrying member 56 which extends substantially parallel to the arm 40 of the bell crank lever 37. A horizontally extending lever member 57 has one end 58 fulcrumed within an aperture in the carrying member 56 and has the other end 59 loosely received within an aperture in the arm 40. The lever member 57 has an aperture midway between its ends 58, 59 which receives one end 60 of a rod member 61. The other end 62 of the rod member 61 is received within an aperture in the upwardly extending portion 36 of the armature 35. Clips 63 which are secured in spaced positions by a convenient method on the rod member 61, such as being in grooves, limit separating movement between the lever member 57 and extended portion 36, which are urged in a separating direction by a helical coil, thrust spring 64 surrounding and longitudinal of the member 62 and having its opposite ends abutting the member 57 and portion 36. The spring 64 transmits the thrust of the armature extended portion 36 to the lever member 57 and exerts sufficient opposing or separating force between the lever member 57 and portion 36 so that upon movement of the armature 35 by the coil 29, toward the lever member 57, the bell crank lever 37 will be pivoted upon its pin 41 and the valve member 47 will be moved into engagement with its stop member 53. The force opposing movement of the bell crank lever 37, upon engagement of valve member 47 with its stop member 53, is now greater than the force exerted by the spring 64, and further movement of the armature 35 into abutting relation with leg 28 is accomplished by compressing the spring 64 which provides lost motion between the magnetic means 24 and the valve 47 so that the armature 35 will abut the magnet leg 28. The spring 64 is given a permanent set, see Fig. 10, so that when off the rod

61 and inert, it is bowed or curved longitudinally, preferably having its longitudinal axis in the form of an arc. The lateral deflection or bowing of the spring is sufficient so that when placed 5 on or sleeved over the rod 61, as in Fig. 9, the spring is tensioned laterally of the rod axis engaging the rod on one side at spaced points and engaging the rod on the other side at an intermediate point. The spring is therefore held in frictional engagement with the rod and opposes movement of the rod through its bore so that when placed in position on the rod member 61, the spring acts as an anti-rattling means. The rod member 61, when the valve is in open position, 10 would, if not for the spring 64, merely lie loosely in the aperture through the member 57 and portion 36 and any vibration which might be caused by the magnetic means 24 15 would rattle the rod member 61 to cause an objectional noise. The spring 64 due to its tendency to assume the shape of an arc, frictionally engages the rod member 61 and as the spring 64 itself is held between the member 57 and portion 36, effectively holds the rod member 61 against vibration. Another feature of this construction is the increased tendency of the 20 spring 64 to prevent vibration, because of the increase in the frictional force due to the compression of spring 64, at the time that the tendency of the rod member 61 to vibrate is greatest, or when the magnetic means 24 is urging the valve 47 in a valve opening direction. The end 25 58 of the lever member 57 is held in fixed position by the carrying member 56, and the end 59 moves the bell crank lever 37 with a force equal to one-half that exerted by the magnetic means 24 but through a distance equal to twice that of the 30 movement of the point of intersection of the rod member 61 and the lever member 57.

40 A thermostatic electric switch means 65 is located within chamber 17 and is carried by a channel supporting member 66 between its outwardly projecting, horizontally spaced side portions 67, 68. A vertical connecting portion 69 has extending flange portions 70, 71 which extend outwardly from vertical edges thereof and are secured by means of screws 72 through the wall 9, and the supporting member 66 is held by the screws 72 in fixed relation to the wall 9. 45 The switch means 65 comprises a temperature sensitive power element 73, a switch arm 74 movable between contact members 75, 76 and 77 to be hereinafter described more fully, and a stop means 78 limiting movement of the switch arm 50 74. The stop means 78 comprises a U-shaped carrying member 79 having its parallel arms 80, 81 of unequal length and having one arm extending on either side of the switch arm 74. The longer arm 81 of the member 79 is spaced 55 vertically above the shorter arm 80 and switch arm 74 and is secured at the open extended end of arm 81 to the lower end 82 of a pin member 83. The pin member 83 extends upward through an aperture 84 extending from a slot or recess 85 in the bottom wall 86 of the supporting block 34 carried by the supporting member 66, and extends above the top wall 87 of the block 34 through an aperture in the cover member 15 60 to terminate, as at 88, exterior to the apparatus. The pin member 83 has an annular projecting shoulder 89 spaced from the lower end 82 and located within the aperture 84. The aperture 84 is of a substantially larger diameter than the 65 pin member shoulder 89. The lower end portion 70 75

90 of the aperture 84 is of reduced diameter to substantially fit and guide the pin member 83 in its reciprocal movement. A metallic cylinder member 91, preferably molded in place at the time the block 34 is fabricated, substantially fits and is secured within the aperture 84 to the block 34. The upper end portion 92 of the cylinder member 91 is internally threaded for reception of an externally threaded cylindrical member 93 having a top end wall 94 with a central aperture therethrough. The internal diameter of the member 93 is of sufficient magnitude to receive the shoulder 89 of the pin member 83, and the upper portion of the pin member 83 is guided by the aperture through the wall 94. The lower end portion 95 of the member 93 projects within the cylinder member 91 so that the extreme lower end forms an adjustable abutment 96 for a disc abutment member 97 held from lateral movement by the internal wall of the member 91. The disk member 97 receives the pin member 83 through a central aperture therethrough so that the member 97 is located concentric with and intermediate the shoulder 89 and end 82 of the pin member 83. A helical coil spring 98 is concentric with the pin member 83 and is held under compression between the portion 90 and the disk member 97, urging the disk member against the abutment 96. A second helical coil spring 99 is located concentric with the pin member 83 and has one end abutting the upper face of the shoulder 89 and the other end abutting the underside of the end wall 94 of the member 93. The spring 99 preferably exerts a force which is substantially equal to one-half that exerted by the spring 98 urging the disk member 97 against the abutment 96. Normally the pin member 83 is urged to the position shown in Fig. 4, but may be either raised or lowered with equal ease by raising or lowering the extending portion 88 which moves the arms 80, 81 relative to the switch arm 74. Upon release of the portion 88, the member 83 assumes its normal position, as shown in Fig. 4. By screwing the cap member 93 in the cylinder member 91, I can space the abutment 96 relative to the portion 90 and thereby change the normal position of the stop means 78 and the open position of the switch arm 74. After adjustment, the cap member 93 is locked in position by a locknut 100 which is threaded to cap member 93 and tightened against the upwardly projecting end wall of the cylinder member 91 to substantially prevent movement of the cap member 93 relative to the cylinder member 91.

The switch means 65, which can be seen in Figs. 5, 6 and 8, has the switch arm 74 and contact members 75, 76 and 77 carried within the slot or recess 85 of the block 34. The arm 74 is a channel-like member having a flat base portion 101 and downwardly extending side portions 102. The base portion 101 has a longitudinally extending slot or aperture 103 therethrough and has at one end portion a downwardly projecting lip 104. The lip 104 has a threaded aperture therethrough in which an adjustment screw 105 is threaded so that a conical end portion 106 thereof is extending beneath the base portion 101 toward the other end 107 of the switch arm 74. The end 107 is pivotally supported by a fulcrum rod member 108 which extends through an aperture in each of the side portions 102. The ends of the rod member 108 are supported on either side of the portions 102 in downwardly extending lugs 109 of a plate-

like member 110 secured, as by screws 111, to the bottom of the recess 85 of the block 34. The plate-like member 110 is thereby insulated from the casing 1. The lugs 109 also serve to prevent lateral movement of the switch arm 74. Intermediate the side portions 102 and below the base portion 101 is a pivoted toggle lever member 112 which has one end portion pivoted on the fulcrum pin or rod member 108 and the other end portion extending toward the lip 104 and being conical in shape, as at 113. The conical portion 113 extends toward the lip 104 in substantial alignment with the aperture 103. The apex of the conical portion 113 is spaced from the apex 15 of the conical end portion 106 of the screw 105, and a resiliently urged, collapsible-expansible toggle member 114 having oppositely extending, conical recessed end portions is under compression therebetween. One recess of the toggle member 114 is received by the conical end portion 113 and the other recess is received by the conical end portion 106. The toggle member 114 is urged in an expandable direction by a spring 115 which urges the conical portions 113, 106 in a separating direction, and the pivoted toggle member 112 in a rotary movement. The spring 115 exerts its force at such an angle on or relative to the member 112 that upon clockwise movement (see Fig. 5) of the member 112 the component of force 20 opposing movement will decrease upon such clockwise movement even though the spring 115 which acts according to Hooke's law actually exerts a greater total force. It will be evident from the foregoing that the force of spring 115 opposing movement of the member 112 varies as the product of total force of the spring 115 and the sine of the angle between the line of the spring 115 and a line connecting the portion 106 with the fulcrum pin 108 of the lever 112. For small acute angles it will be noted that the sine will decrease with greater rapidity than the increasing of force of the spring 115 upon compression. I have found that a spring having a rate of increase of force of 5 pounds per inch and acting through a maximum angle of $3\frac{1}{2}$ degrees will work in this apparatus to give a satisfactory decrease in movement of force. The rotary movement of the toggle member 112 is limited to the foregoing acute angle by a pair of adjustment screws 116, 117 threaded in apertures through the member 112 so that upon initial movement of the member 112 the member 112 will move throughout its range of movement due to the breakdown of the opposing force of spring 115. The screws 116, 117 also locate the end points of travel of the conical end portion 113 in respect to the bottom of the recess 85 by their engagement with the plate-like member 110. The adjustment screw 105 acts to determine the magnitude of force exerted by the spring 115 and thereby to determine the differential of operation of the power element 73.

The temperature sensitive power element 73 comprises a cap member 119 having its open end portion 120 secured by means of screws 121 to the lower face of the horizontally spaced side portion 68 of the channel member 66. A bellows member 122 located within the cap member 119 has one end secured in fluid-tight relation to the end portion 120 of the cap member and has the other end of the bellows member sealed to a reentrant movable end wall 123 located within the cap member 119 to form an expansible-collapsible chamber 124. A temperature sensitive bulb 125 is connected by means of a suitable flexible, small bore

tubing 127 to the interior of the chamber 124 and a closed system 128 is formed thereby. The system 128 is evacuated and charged with a predetermined quantity of temperature sensitive, volatile fluid so that with increasing temperature of the bulb 125 the pressure within chamber 124 will increase and urge the movable end wall 123 outwardly toward the open end 120 of the cap member 119 with increasing force.

An internally threaded, cylindrical member 129 having an end wall 130 is secured in fluid-tight relationship within a concentric aperture through the reentrant portion of the movable end wall 123. The end wall 130 is within the chamber 124 and has a central aperture therethrough in which is sealed one end of a short piece of tubing 131 which is suitably closed at its other end, externally of the member 129, subsequent to the tubing 131 being used for charging the system 128 with the volatile fluid. The member 123 has a shoulder 132 within the chamber 124 which forms an abutment and guide for one end of a helical coil spring 133 held under compression between the portion 132 and the inner end wall of cap member 119. The spring 133 is operable in conjunction with the fluid pressure in chamber 124 to urge the wall 123 in an outward direction or toward the lever 112. The spring 133 is preferably one having a rate of force increase of 28 pounds per inch of length decrease. A screw-threaded, hollow thrust member 134 extends outwardly and is threaded into the cylindrical member 129 surrounding the tubing 131, and carries at its upward end a member 135^a of electric insulating material. The member 135^a carries a conical member 136 the apex of which is received in a conical recess in the lower wall of the pivoted member 112. The length of the upwardly extending thrust member 134 may be adjusted relative to the member 129 by screwing so that the upwardly extending conical end portion 136 is in proper space relation with the pivoted member 112.

Rotational movement of the pivoted member 112 by the upward movement of the thrust member 134 is opposed by a downwardly extending thrust member 137 of electric insulating material which has a conical end portion 138 received within a conical recess 139 in the upper wall of the member 112. The member 112 is electrically insulated by the member 135^a and thrust member 137, and the molded block 34, from the casing 1 to electrically isolate the switch arm 74. The thrust member 137 is urged toward the member 112 by a helical coil range spring 140 held under compression against the thrust member 137 by an adjustable abutment member 141 screw-threaded, as at 142, in a nut member 143 secured within an aperture in the side portion 67 of the channel member 66 so that the member 141 is operable to be moved relative to the thrust member 137 to change the acting force of the spring 140. A suitable knob means 144 carried by and removable with the cover member 15 has operative connection with member 141 through a radially extending pin 145 extending from the member 141 into a slot 146 of the means 144. An upwardly extending stop pin 146^a cooperates with the pin 145 to limit rotation of the member 141 to less than 360°. The downward force exerted by the spring 140, which acts in opposition to the upward force exerted through the cylindrical member 129, may be adjusted externally of the apparatus by the knob means 144 to change the temperature at which bulb 125 will rotate the pivoted member

112. A spring with an increase in force of 41 pounds per inch decrease in length is satisfactory. The particular characteristics of the springs 115, 133 and 140 depend upon the magnitude of the acute angle formed between the member 112 and a line joining the conical portion 106 to the fulcrum pin 108. The member 112 in this instance is arranged so that the spring 115 engages the member 122 one inch from the fulcrum pin 108 and the springs 133 and 140 and power element 73 engage the member 112 one-eighth inch from the fulcrum pin 108. The springs are so arranged that the moment of force exerted by the spring 115 decreases more rapidly than the algebraic sum of the moments of force caused by the decrease of force of spring 133 and increase of force of spring 140, the resilience of the bellows 122 being taken into consideration as part of the spring 133.

The contact members 75, 76 are positioned above the arms 74 and are carried by one end of current conducting spring members 147, 148 respectively. The spring members 147, 148 are secured adjacent to but in spaced relation with the bottom of the recess 85 at the end opposite to the contact members 75, 76 to binding post members 149, 32 which are preferably molded into the block 34. The contact member 77 is carried below the switch arm 74 by a U-shaped current conducting, supporting member 151 having a pair of parallel arms 152, 152^a. One parallel arm 152 is attached to the post member 149 and the other parallel arm 152^a, to which the contact member 77 is secured, extends below the switch arm 74. The switch arm 74 is connected by a lead wire 153 to a binding post member 154 molded in the block 34. An electric conducting strip 155 also molded within the block 34 connects a binding post member 156 to the binding post member 33 to which the lead wire 31 is fastened.

When the switch arm 74 is in the position shown in Fig. 5, the switch arm will be in engagement with contact members 75, 76. The conical portion 113 is held from further counterclockwise rotational movement by the adjustment screw 117, and the force of the spring 115 of the collapsible-expansible toggle member 114, acting between the portion 106 and member 112, will flex the spring members 147, 148 until the contact carrying ends thereof are in engagement with the bottom wall of the recess 85. This flexion of the spring members 147, 148 will occur after contact has been made by the switch arm 74 and will cause a wiping action between the contact members 75, 76 and the adjacent surface of arm 74 and insure a good electrical contact therebetween. As the pivoted toggle member 112 is rotated in a clockwise direction by the power element 73, the conical end portion 113 thereof will pass the line of centers between the conical portion 106 carried by the switch arm 74 and the fulcrum rod member 108, and the arm 74 will move in a counterclockwise direction with increasing velocity due to the expansive force of the toggle member 114. The spring members 147, 148 will follow the movement of the switch arm 74 due to the resilient force urging the contacts to their spaced position from the bottom wall 86, and will keep the contact members 75, 76 in electrical contact with the switch arm 74 until the arm has gained speed enough to make a quick break with the contacts.

The arm 74 is stopped in its opening movement and is prevented from engaging the contact member 77 by the engagement of the arm

14 with the underlying arm 80 of the stop means 78. The switch then normally remains in open circuit position until closed by the spring 140 acting in opposition to the power element 73. Should it be desired to close the circuit through contact member 77, it is necessary to push downward the portion 88 of the pin member 83. The arm 80 against which the arm 74 is urged by toggle member 114 is thereby lowered and the arm 74 is permitted to move into engagement with the contact member 77 under the expansive force of the toggle member 114. Upon release of the portion 88, the spring 98 will move the stop arm 80 to its normal position above that of contact member 77 to open the circuit between contact arm 74 and the member 77. Should it be desired that the circuit between arm 74 and contact members 75, 76 be closed and the switch arm 74 is in open circuit position, due to the power element 73, the portion 88 may be raised manually so that the arm 80 will lift the arm 74 against the force of the toggle member 114 into contact making position. Release of the pin member portion 88 will cause the arm 80 to be moved to its normal position by the spring 98, and the toggle member 114 will then be effective to urge the arm 74 to open circuit position.

Now let us assume that the switch arm 74 is in the position shown in Fig. 5, that is, with the temperature sensitive bulb 125 at a lower temperature than the predetermined temperature for which the switch is set to open the circuit between switch arm 74 and contacts 75, 76. The switch arm 74 can now be moved manually from contact members 75, 76 to open the circuits therebetween by depressing the portion 88. The arm 81 will engage the switch arm 74 and move it against the force of the toggle member 114. Further movement of the portion 88 downward will move the switch arm 74 into circuit making relation with the contact member 77. Release of the portion 88 will allow spring 98 to move the stop arms 80, 81 to normal position and the expansive toggle member 114 will move the arm 74 to contact making position with contact members 75, 76.

The application of the apparatus described may be seen from the diagrammatic view of a water heating system shown in Fig. 1. The numeral 200 represents generally my apparatus hereinbefore described, supplied with electrical energy through lead wires 201, 202 connected to a suitable source of supply. An electric air supplying means 203 is supplied with electrical energy by lead lines 204, 205 connected to the switch means 65 of the apparatus 200. The output of air from the means 203 is directed through a conduit means 206 to the liquid fuel burner 50, supplied with a suitable liquid fuel by the conduit means 49 from the apparatus 200. The heat output of the burner 50 is directed toward a suitable hot water tank 207 connected into a suitable hot water system (not shown). The temperature sensitive bulb 125 is located within a suitable bulb well 208 in heat exchange relation with the water in the tank 207 and is connected by the small bore tubing 127 to the apparatus 200.

The schematic view shown in Fig. 2 in which like parts to other figures are designated by the same numerals shows clearly the electrical circuit of my apparatus 200 connected to the equipment described in connection with Fig. 1. Lead wire 201 is connected directly to the binding post member 149 and thereby to the connected contact members 75, 77. The other lead wire 202

from the electrical supply is connected to the terminal post 156. The lead wire 205 is connected to the post 156 and to the electric air supplying means 203, and the other lead wire 204 connected to the supplying means 203 is connected at its opposite end to the terminal post 154 which is electrically connected to the switch arm 74. The terminal post 33 is connected to one lead wire 31 of the magnetic coil 29 and the other lead wire 30 of the coil 29 is connected to the terminal post 32 and therethrough to the directly connected contact member 76. In connecting my equipment in this manner to the switch means, I substantially prevent the undesirable circumstance of having the oil valve 47 held open by the magnetic means 24 and the air supply means 203 deenergized. Each means 24, 203 is supplied directly by the lead wire 202. The lead wire 204 connects the means 203 directly to the switch arm 74. The lead wire 201 is directly connected to the contact members 75, 77 and the means 24 is directly connected by lead wire 31 to the contact member 76. If the switch arm 74 is in any contact making relation with member 75 or 77, the circuit through the means 203 must necessarily be closed. The switch arm 74 must necessarily be in circuit making relation to the lead-wire 201 to be able to complete the electrical circuit through the magnetic means 24, even though contact member 76 should possibly through any chance be in circuit making relation with the switch arm 74. It has been shown that any time the arm 74 is in circuit making relation with wire 201, the means 203 is electrically connected to the supply, and as the arm 74 must be in contact with member 75 or 77 to energize the magnetic means 24, there is therefore no chance of having the valve member 47 open without the air supply means 203 being energized, even though the contacts should arc and stick together.

In operation my device works as follows: Assuming the water in tank 207 to be at a lower temperature than the minimum predetermined temperature for which the apparatus 200 is set to operate, the fluid pressure in the sealed system 128 will be relatively low and the switch means 65 will be in the position shown in Fig. 5. The magnetic coil 29 will be energized and holding the armature 35 against the leg 28. The valve member 47 will be against its stop member 53 in maximum open position and the oil will flow through the conduit 49 from the chamber 22 and into the burner 50. The switch means 65 will also be making circuit through the electric air supplying means 203 and the air requisite to insure proper operation of the burner 50 will be supplied. The heat output from the burner 50 is absorbed by the water in tank 207 thereby raising its temperature. When the predetermined maximum temperature for which the thermostatic switch means 65 is set to operate is reached, the pressure within the system 128 will have increased sufficiently to force the movable wall 123 outward from the cap member 119 in opposition to the opposing force of the spring 140. The pivoted toggle member 112 will upon initial movement by the power element 73 move throughout its range of movement without any additional increase in the force exerted by the element 73 due to the breakdown of forces opposing movement of the member 112. It will be noted that while the total force exerted by the spring 115 increases upon movement of the member 112 in a clockwise direction (see Fig. 5) the component

of force of the spring 115 actually decreases due to the angle at which it acts on the member 112 and the moment of force exerted on the member 112 decreases. The decrease of moment of force must be greater than the algebraic sum of the decrease of moment of force of the spring 133 and the increase in opposing force due to the collapsing of the bellows member 122 and of the spring 140. Upon movement of portion 113 into the line of centers of portion 106 and the fulcrum pin or rod member 108 moment of force of spring 115 exerted in opposition to movement of the member 112 is zero and upon a slight further movement of the member 112 in the clockwise direction the moment of force exerted by the spring 115 in fact acts to aid the power element in its movement of the member 112. The additional aiding moment of force exerted by the spring 115 increases upon continued movement of the member 112 due to the angle of operation of spring 115 with respect to member 112 and is true even though the total force exerted by the spring 115 decreases upon spring expansion. As the portion 113, portion 106 and centerline of the spring 115 pass overcenter the spring which, of course exerts a reactionary force in the opposite direction of an equal magnitude to that exerted in the first direction acts to move the switch arm 74 in a counterclockwise direction (see Fig. 5) with an increasing force and consequently increasing arm velocity due to the change in angle at which the force of the spring 115 acts on the switch arm 74. Not only does the present construction allow for a quick break due to the increase in the force exerted by the spring 115 on the arm 74 but also the spring members 147, 148 act to move the contact members 75, 76 respectively, against the arm 74 until the arm 74 is travelling at a high rate of speed thereby preventing excessive arcing when the contact members part due to a prolonged positioning of the contact members 75, 76 in arcing relation with the arm 74.

As was stated hereinbefore the thermo sensitive bulb 125, responsive to the temperature of the controlled medium, is connected for purposes of convenience by a small bore or capillary tube 127 to the power element 73. As the power element 73 moves the member 112, the volume of the chamber 124 increases and if the pressure therein is to remain constant or in balance with the pressure of the volatile fluid within the bulb 125 additional fluid must be supplied thereto from the bulb 125 and this additional fluid must pass through the capillary tube 127. Movement of a quantity of fluid through a small bore or capillary tube requires an elapse of time and therefore the bellows member 122 cannot immediately with a rapid movement move from its switch closed position to its switch open position but must move with a relatively slower movement depending upon the rate of breakdown of the opposing forces and the rapidity with which the fluid will flow from the bulb 125 through the capillary tube 127 to chamber 124 in an effort to maintain the predetermined high pressure in the chamber 124 corresponding to the predetermined high pressure in bulb 125 caused by the predetermined maximum temperature for which the switch means is set to operate.

The power element 73 and member 112 it is seen operates with a snap action insofar as the forces having once started movement, the members will not again come into equilibrium until they have moved into their final position but the

movement is of a relatively slow action when viewed with the speed at which the arm 74 moves through its range of movement. The spring 115 has no time lag in its operation and will act to move the switch arm 74 with a substantially instantaneous movement for fast switch operation. The construction embodied therefore has the advantage of a quick breaking switch mechanism while still retaining the use of a small bore tubing which is flexible and easily handled. The pivoted toggle member 112 therefore rotates clockwise with a slow snap action and the switch arm 74 opens the circuits to the magnetic coil 29 through the contact member 76 and to the air supplying means 203 through contact 75 with a fast snap action. The armature 35 will rotate counterclockwise, as seen in Fig. 4, allowing the bell crank lever 37 to rotate clockwise and the valve member 47 to move vertically downward to engage its minimum stop 54. The valve member 47 when against its stop member 54 is preferably set to deliver a minimum flow of fuel to the burner 50 so that proper combustion therein with air being supplied by natural convection will occur and the burner 50 will stay ignited. The heat output under this condition is preferably sufficient to maintain the water at the given predetermined temperature, but sufficiently low so that there is no danger of the water becoming too hot.

As there becomes a demand for hot water from the system, the burner 50 under minimum fuel flow conditions is unable to maintain the water above the predetermined minimum temperature for which the apparatus is set to open. As the water temperature drops, the bulb temperature also decreases with a decrease of the pressure in the closed system 128, until the force exerted by spring 140 overcomes the opening force of the end wall member 123. The pivoted toggle member 112 will then rotate counterclockwise causing the switch arm 74 to rotate with a snap action clockwise into circuit making position with the contact members 75, 76 to energize the air supplying means 203, which will then supply the required extra air to the burner 50. The coil 29 also being energized, the armature 35 will be drawn toward the leg 28 and the valve member 47 will be lifted by the bell crank lever 37 against its upper stop member 53 to increase the flow of fuel to the burner 50. The valve member 47 preferably engages its stop member 53 before the armature 35 engages the leg 28 and thereby is prevented from further movement in an open direction. The bell crank lever member 37 is prevented from further counterclockwise rotation and the spring 64 compresses under the closing force of the magnetic means 24 and operates as a lost-motion means to allow the armature 35 to engage the magnet leg 28. Engagement of the armature 35 and leg 28 is necessary to prevent the armature from vibrating under the influence of the coil 29 and causing a humming noise.

The differential temperature necessary to operate the switch may be adjusted by screwing the cylinder member 93 in the member 91 to raise or lower the abutment 96, which causes the switch arm 74 to stop its movement in an open circuit direction closer or further away from the line of center of the conical portions 106, 113 and fulcrum rod member 108 so that the movement of force exerted by the expansible-contractible toggle member 114 is lessened or increased to demand a corresponding change in pressure with the system 128 to exert the necessary force on the thrust

member 134. This adjustment is usually made upon manufacture of the apparatus. The only adjustment designed to be made in the field is the range adjustment controlled by the knob means 144, and which may be adjusted by rotation of the knob means to increase or decrease the force of the spring 148.

This application is a division of my copending application Serial No. 410,842, filed September 15, 1941, for Heating systems and control means therefor, which is a division of Patent No. 2,259,645, dated October 21, 1941.

What is claimed and desired to be secured by Letters Patent of the United States is:

1. In a heating apparatus, a fluid fuel burner, electrically operated means for supplying air to said burner, electrically operated means for supplying fuel to said burner, switch means having a pair of fixed contact members and a movable switch arm operable on movement in one direction to make circuit simultaneously with said members, said contact members being electrically connected respectively to a source of current supply and to said electrically operated fuel supplying means, said arm being electrically connected to said air supplying means so that said air supplying means will be energized whenever said fuel supplying means is energized, a contact member engageable by said switch arm upon movement of said switch arm in the opposite direction and electrically connected to the source of current supply, means to stop movement of said switch arm into engagement with said last-named contact member, and means to move said switch arm in said opposite direction to engage said last-named contact member.

2. In a heating apparatus, a fluid fuel burner, electrically operated means for supplying air to said burner, electrically operated means for supplying fuel to said burner, switch means having a pair of fixed contact members and a movable

switch arm operable on movement in one direction to make circuit simultaneously with said members, said contact members being electrically connected respectively to a source of current supply and to said electrically operated fuel supplying means, said arm being electrically connected to said air supplying means so that said air supplying means will be energized whenever said fuel supplying means is energized, a contact member engageable by said switch arm upon movement in the opposite direction and electrically connected to the source of current supply, and manually operable means controlling the engagement of said switch arm with said last-named contact member.

3. In a heating apparatus, a fluid fuel burner, electrically operated means for supplying air to said burner, electrically operated means for supplying fuel to said burner, switch means having a pair of fixed contact members and a movable switch arm operable to make circuit simultaneously with said members, thermostatic means operable to move said switch arm into engagement with said fixed contacts, said switch arm having a lost-motion connection to said thermostatic means for movement of said switch arm irrespective of said thermostatic means, manually operable means cooperable with said connection to move said switch arm relative to said thermostatic means, said contact members being electrically connected respectively to a source of current supply and to said electrically operated fuel supplying means, said arm being electrically connected to said air supplying means so that said air supplying means will be energized whenever said fuel supplying means is energized, and a contact member connected to the source of current supply and engaged by said arm upon operation of said arm by said manually operable means.

WALTER S. LANDON.
